UNITED STATES PATENT OFFICE.

ENOS B. WILLIX, OF DYSART, IOWA.

MACHINE FOR APPLYING VERTICAL STAY-WIRES IN WIRE FENCES.

SPECIFICATION forming part of Letters Patent No. 600,569, dated March 15, 1898.

Application filed December 10, 1896. Serial No. 615,245. (No model.)

To all whom it may concern:

Be it known that I, ENOS B. WILLIX, a citizen of the United States of America, and a resident of Dysart, in the county of Tama and State of Iowa, have invented a new and useful Machine for Applying Vertical Stay-Wires in Wire Fences, of which the following is a specification.

The object of this invention is to provide improved means or mechanism for constructing a fence and in which the stability and positioning of smooth fence wires or strands are assured and sustained.

A further object of this invention is to provide improved means for making a fence by mechanically applying to smooth strands of a fence cross stays or wires, the body portions of which cross stays or wires are twisted upon the strands.

My invention consists in the first instance in mechanically and automatically combining with the smooth strands of a wire fence cross-stays, the body portions of which stays are twisted upon the said strands.

My invention consists, further, in a machine for applying the stays to and winding the body portions thereof upon the strands of the fence, which machine comprises revoluble twisting devices arranged to revolve about

the strands of the fence and means whereby the body portions of the stays are engaged by said revoluble twisting devices and caused to wind upon and rigidly embrace and engage the strands.

My invention consists, further, in a twisting device comprising a shaft slotted laterally beyond its center and longitudinally its entire length, means for driving said shaft revolubly, and a twisting or winding bit mounted upon the said shaft and arranged to engage a wire.

My invention consists, further, in a machine comprising a shaft, bearings for said shaft, a twister upon said shaft, the shaft, bearing, and twister being slotted from one side beyond the axis of the shaft and twister to admit a fence-strand, and means for revolubly moving the said shaft and twister relative to a fence-strand.

My invention consists, further, in a twister or winding device comprising a head slotted laterally beyond the axis thereof, which head

is recessed from and at right angles to the slot therein, a face-plate inclosing the recess and slotted coincident with the head and notched 55 coincident with the recess in the head, but to a less degree, and a winding-bit removably, replaceably, and adjustably mounted in the recess of the head and projecting over the slot in said head and arranged to engage a wire or 60 a projection therefrom traversing the recess in the head.

My invention consists, further, in a plurality of revoluble shafts, a plurality of gears arranged upon said shafts, driving-racks engaging said gears, means for actuating said racks and twisters or winding devices mounted upon the shafts.

My invention consists, further, in the combination of a shaft slotted laterally and longitudinally from end to end and from its periphery beyond its center, a gear mounted upon said shaft and slotted coincident with the slot in the shaft, a winding device mounted upon said shaft and slotted coincident with 75 the slot in the shaft and in the gear, and bearings whereby said shaft is revolubly mounted, which bearings are slotted coincident with the slots in the shaft, gear, and winding device.

My invention consists, further, in the construction of a machine comprising a frame, shafts mounted thereon, gears on the shafts, bearings connecting the shafts and frame, winding devices upon the shafts, and means 85 for actuating the gears, the shafts, gears, winding devices, and bearings being coincidently slotted for the insertion and removal therefrom of fence-strands.

My invention consists, further, in the construction of a gear-wheel in halves and provided with means for attaching said wheel to a shaft, which wheel is slotted radially from its periphery to a point beyond its axis.

My invention consists, further, in a wheel 95 diametrically divided and recessed on the lines of division to form a slot from a point on its periphery to and beyond its axis.

My invention consists, further, in the construction, arrangement, and combination of 100 elements hereinafter set forth, pointed out in my claims, and illustrated by the accompanying drawings, in which—

Figure 1 is an elevation of a panel of the

fence. Fig. 2 is an edge view thereof. Fig. 3 is a plan in part of the machine employed to make the fence. Fig. 4 is an elevation of the machine shown in Fig. 3, partly in section. Fig. 5 is a plan, and Fig. 6 is an elevation, in detail illustrating the construction of the divided and recessed gear-wheel, the construction of the slotted shaft, and the manner of applying the divided and recessed gear-wheel to the slotted shaft. Fig. 7 is a rear elevation, and Fig. 8 is an end elevation, of one of the twisters or winding devices, Fig. 8 also showing the manner of locating a stay in relation to the winding device for practical use. Fig. 9 is an elevation in detail of one of the bearings, which also serves as a guide to direct the approximation of the machine and the fence-strands.

In the construction of the fence illustrated in Figs. 1 and 2 and made, preferably, by the machine hereinafter described the numerals 10, 11, 12, 13, 14, 15, 16, 17, 18, 19, and 20 designate the fence wires or strands, which may vary in size, number, and relative positioning, as desired.

To the strands above mentioned there are attached a plurality of stays 21 22, of like construction, which stays are illustrated and described in my application for United States Letters Patent, Serial No. 615,244, filed December 10, 1896, and pending concurrently herewith. Reference to the above concurrent application will disclose that each of the stays is formed with a plurality of laterally-extending and parallel-positioned tongues, which are arranged to be wrapped around, upon, or twisted to the strands of the fence.

In this application, as illustrated in Figs. 1 and 2, the tongues are shown as being coiled upon the strands of the fence and designated by the numerals 23. It will be observed that the coils 23 on the stay 21 project toward the stay 22 and that the coils 23 on the stay 22 project toward the stay 21. The drawings illustrate the invention in that manner, because it has been found by experiment to be more convenient to apply two of the said wires to the strands of the fence simultaneously than separately, and it is not considered necessary to illustrate the application of more than two of the stays to the fence-strands, and therefore this application is drawn and the illustration made to conform thereby to the idea that the machine applies two stays simultaneously to the fence-strands.

In order to apply the stays to the fence-strands, it is desirable that a machine be provided, and when such machine is provided it is further desirable to provide means for approximating and separating the machine and the strands in order that the machine may be adjusted relative to the length of the fence or the fence fed to and taken away from the machine.

With the above idea in view I have constructed a machine as illustrated in Figs. 3, 4, 5, 6, 7, 8, and 9. In this machine as illus-

trated the numerals 24 25 designate bars which are provided with transversely-positioned grooves 26 27, arranged in alinement with each other and at such distances of separation as it is desired the strands of the completed fence shall be located. The strands of the fence are positioned in the grooves 26 27, or if the bars 24 25 are omitted the said strands of the fence are connected at their forward ends to some means (not shown) whereby they may be advanced and are supported at their rear ends, as coils of wire, upon mechanism whereby they may be permitted to advance from the coil and be acted upon by the machine which applies the stays thereto. Positioned in a horizontal plane above the bars 24 25 or the horizontal plane of travel of the strands of the fence are a plurality of bearings 28, Fig. 9, which bearings are connected at their upper ends by beams 29, which beams in turn are connected by cross-bars 30. By this means a frame is formed by which the operating elements of the machine are supported, and this frame may be varied in its construction, shape, or appurtenances without regard to the illustration in this application, it being desired herein only to show a means whereby the operating devices of the machine may be supported to do the work required of them.

The frame just described in practical use should be supported so as to be lifted away from the horizontal plane or path of travel of the fence-strands or should be so arranged relative to the mechanism controlling the fence-strands as that said strands may be moved away or out of the horizontal plane of the frame, but it is believed to be the preferable construction to suspend the frame relative to the wires, so that it can be lifted clear therefrom. The bearings 28 are bifurcated in their body and lower end portions and the extremities of the arms forming the bifurcations thereof are beveled, rounded, or chamfered in order that in the approximation of the bearings to the wires the extremities of the arms may have more expanse or spread to compass and confine the strands against lateral movement. In acting upon or employing wire in the mechanical arts it has been found necessary to control and limit the lateral movement of the wire at all times, since one of its inherent peculiarities is to buckle, bend, spring, warp, twist, and move about in different directions uncontrollably, save by mechanical engaging means. Mounted within and rotatable relative to the bearings 28 are shafts 31, the axes of which shafts are in vertical planes coincident with the planes connecting opposite grooves 26 27, and said shafts are slotted their entire lengths and transversely beyond the axes thereof, as indicated by the numerals 32. The shafts are susceptible to such positioning, Fig. 4, as that the grooves therein will aline or register with the bifurcations of the bearings and be directed downwardly.

5 Mounted on the shafts 31 are gears 33, which gears are formed in halves *a b* or diametrically divided and bossed at 34 35 36 37 with integral projections, the projections or bosses being transversely apertured above the grooves of the shafts when said grooves project downwardly to receive bolts 38, whereby the separate sections *a b* of the gears may be connected and clamped to and upon the shafts. The 10 gears may also be keyed upon the shafts or secured by set-screws, if desired. The gear sections *a b* and the bosses thereon are recessed opposite to the line of separation or diametrical line of division of the gears to 15 form a slot or groove 39 in the completed gear when attached to the shaft in alignment or registration with the groove 32 of the shaft.

Since it sometimes occurs, as illustrated at the right end of Fig. 3, that the shafts 31 are 20 arranged in such close relations as that the spaces between them are not so great as that of the diameter of the gears 33, it is desirable to locate the gears 33 in staggered relations to each other alternately in the machine. The 25 gears 33 are revolvably driven by racks 40 41, which racks are connected conjunctively to a motive power, in this instance a hand-lever 42, fulcrumed at one end of the machine and arranged for manual operation to reciprocate 30 the racks. The racks are held down to and in engagement with the gears 33 by the cross-bars 30 of the frame or any other desired manner.

In each end of each of the shafts 31 there 35 is mounted a twisting device, the twisting devices on one side of the machine being oppositely arranged relative to the twisting devices on the other side of the machine. The twisting devices are identical in form. There- 40 fore I will describe one only of them. A twisting head 43, made of a single block of metal, is countersunk or reamed out at one side, as shown by dotted lines in the left of Fig. 7 and by the dotted circle in Fig. 8, and in the re- 45 cess or depression thus formed one end portion of the shaft 31 is inserted and secured rigidly by brazing or other secure fastening. The head 43 is slotted radially at 44 in alignment with the slot 32 of the shaft upon which 50 said head is mounted and in alignment with the slot 39 in the gear 33, also mounted upon said shaft. The interior of the head 43 is provided with a recess or cavity 45, leading from the slot or groove 44 rearwardly, as the 55 machine is positioned in the first instance, entirely through the head. The recess 45 is shown in Fig. 7 and outlined by dotted and solid lines in Fig. 8. The formation of the slot or groove 44 in the head 43 provides that 60 the forward portion of said head forms a hook, for convenience designated 46, and the lower extremity of said hook is chamfered or beveled away from the groove 44 to provide for the more convenient positioning of the 65 strand within the said groove. A face-plate 47 is mounted on the face of the head 43 opposite to the end portion of the shaft 31, which

engages said head and is made to conform in general contour to said head. A slot is formed in the face-plate 47 coincident with the slot 44 of the head, with this exception, that the slot in the face-plate is wider and the sides thereof diverge more abruptly than do the sides of the slot in the head, and the forward side or hook portion of the face-plate is beveled away from the slot therein along one side of said slot and over the top thereof. A notch 48 is formed in the face-plate and connects with the slot therein and extends rearwardly therefrom, and the said face-plate is beveled on its interior from said notch rearwardly, as indicated by dotted line 60 in Fig. 8.

The purpose of the beveling or chamfering of the outer corner of the face-plate 47 adjacent to the slot in the face-plate and of the 85 inner corner of the face-plate adjacent to and in the rear of the notch in the face-plate is to permit of the positioning of the tongue 49 of the stay-wire 21 or 22 in the notch and behind the face-plate and through the recess 90 or cavity 45 of the head 43, and at the same time provide that said tongue and the stay of which it forms a part shall be twisted to the minimum degree. The face-plate 47 is secured to the head 43 by the screws 50, located 95 on opposite sides of the cavity in said head. A twisting bit or plate 51 is positioned in the cavity of the head 43 and is inclined rearwardly and downwardly, the front edge of the bit 51 being cut on a level to the planes 100 of its top and bottom surfaces and coinciding or registering with the rear of the slot 44. The bit 51 is secured to the head by a screw 52, traversing the lower portion of said head and seated in the said bit. 105

When the machine above described is practically employed in making the fence above described, the series of shafts and the gears and twisting devices carried thereby are so arranged as that the slots therein are directed downwardly and register with the slots or bifurcations of the bearings 28. The machine is then approximated to the strands of the fence, and said strands enter the bifurcations of the bearings 28 and are guided thereby into the slots and grooves of the gears 33, the twisting devices, and the shafts 31. Two of the stay-wires 21 22 are then thrust alongside of the twisting devices at either end of the shafts, so that their loops 61 inclose the 110 strands seated approximately at the axes of the shafts and so that the tongues 49 of the said wires lie within the recesses 45 of the heads 43 and within the notches 48 of the face-plate and between the strands of the 115 fence and the bits 51 of the twisting devices, the said bits 51 engaging beneath the said tongues in close proximity to the axes of rotation of the shafts, as clearly illustrated in Fig. 8. The racks 40 41 are then moved in 120 the direction of the arrow 53 in Fig. 3 to the limit of travel of the said racks, which limit of travel preferably is such as to permit of 125 and cause three complete revolutions of the

gears 33 and through said gears of the shafts and twisting devices. In the rotation of the shafts said shafts revolve about and upon the strands of the fence. In the rotation of the twisting devices the bits 51 engage the tongues 49 and carry the same around the strands to the formation of coils 23, as illustrated in Fig. 1, the coils forming within the recesses or cavities 45 of the head 43.

10 When the coils are formed, by the winding of the tongues around the strands, the slots of the twisting devices are again in positions at which they started, and the machine is separated from the strands and stays and adjusted at the desired distance from the stays and reoperated, and during the period of adjustment the racks are moved longitudinally in the direction opposite to that indicated by the arrow 53 in Fig. 3 and into the positions 15 at which they started.

I claim as my invention—

1. A machine for applying a stay to and winding the body portions thereof upon the strands of a fence, which machine comprises 25 twisting devices arranged to revolve about the strands of a fence, which revoluble twisting devices comprise shafts, heads, and bits, the heads being apertured transversely to receive the fence-stays and bits, whereby the body portions of the stays are engaged and caused to wind upon and rigidly embrace and engage the strands.

2. A twisting device comprising a shaft slotted laterally beyond its center and longitudinally its entire length, means for driving said shaft revolvably, a twisting or winding head mounted upon said shaft, and a twisting or winding bit removably and replaceably mounted in said head and arranged to engage 40 a wire.

3. A machine comprising a shaft, bearings on said shaft, a twisting-head upon said shaft, the shaft, bearing and head being slotted from one side beyond the axis of the shaft and head 45 to admit a strand, a winding-bit mounted in said head and extending to the slot therein, and means for revolvably moving said shaft and head relative to said fence-strand, whereby the winding-bit is carried around the fence-50 strand.

4. A twister or winding device comprising a head, slotted laterally beyond the axis thereof, which head is recessed from and at

right angles to the slot therein, a face-plate inclosing the recess and slotted coincident 55 with the head and notched coincident with the recess in the head but to a less degree, and a winding-bit removably, replaceably and adjustably mounted in the recess of the head and projected over the slot in said head and 60 arranged to engage a wire or a projection therefrom traversing the recess in the head.

5. A wheel diametrically divided and recessed on the lines of division to form a slot from a point on the periphery of said wheel 65 to and beyond its axis, in combination with a shaft similarly slotted and bosses 34, 35, 36, 37, fixed to and laterally extending from opposite sides of said wheel, which bosses are arranged to be rigidly connected by bolts 38 70 traversing said bosses on one side only of the axis of the wheel to connect the halves of the said wheel firmly to the shaft, the bosses also recessed on their lines of separation coincident with the slot in the wheel. 75

6. In a machine of the class described, bars 24 and 25 provided with transverse alining notches in their upper faces to receive and guide strand-wires, a frame shaped and arranged for vertical removal and replacement 80 relative to said bars, bearings 28 on opposite sides of said frame and projecting downwardly therefrom, which bearings are bifurcated and tapered or spread at their lower ends, shafts 31 mounted for rotation in said 85 bearings and slotted from end to end and from one side to and beyond their axes, diametrically divided and slotted gear-wheels mounted on said shafts, bosses fixed to the gear-wheel and clamped fast to the shafts, 90 which bosses are slotted coincident with the wheels, twisting-heads mounted on the shafts and transversely apertured to receive stay-wires and slotted coincident with the shafts to receive strand-wires, winding-bits removably, replaceably, and adjustably mounted in the apertures of the winding-heads and extending to the slots therein, racks arranged 95 for rectilinear reciprocation on the frame and meshing with said gear-wheels, and means for 100 operating said racks.
